UNITED STATES PATENT OFFICE.

WILLIAM E. GREENAWALT, OF DENVER, COLORADO.

APPARATUS FOR TREATING LIQUIDS WITH GASES.

1,374,500.

Specification of Letters Patent. Patented Apr. 12, 1921.

Application filed October 30, 1915, Serial No. 58,748. Renewed February 12, 1920. Serial No. 358,130.

To all whom it may concern:

Be it known that I, WILLIAM E. GREENAWALT, a citizen of the United States, residing in the city and county of Denver and 5 State of Colorado, have invented certain new and useful Improvements in Apparatus for Treating Liquids with Gases, of which the following is a specification.

The invention has for its more immediate 10 object the effective application of gases to liquids to accomplish certain results, as, for example, the precipitation of metals from their solutions by a gas such as hydrogen sulfid, or in the flotation treatment of certain ores. It is not intended, however, to 15 limit it to any particular use, although in describing the apparatus the above mentioned uses will be kept more or less in mind.

This application may be regarded as an 20 improvement in part thereon of my pending applications, Serial No. 812,951, filed January 19, 1914, and Serial No. 845,011, filed June 13, 1914.

Referring to the accompanying drawing, 25 1 is a tank containing a liquid and the material to be treated, 2 is a hood suspended within the tank and submerged in the liquid, and having perforations 3, through which gases may be passed from the inside of the 30 hood to the liquid in the tank. 4 is a shaft, rotating on bearings 5, by means of which the hood is suspended and rotated within the tank, when driven by the pulley 6. 7 is a feed hopper, by means of which the 35 material to be treated is fed into the tank. This feed hopper may vary in length, depending upon the material to be treated. Its bottom opening may be submerged in the liquid in treating some material, while for the treatment of other material it may be shortened, 40 as shown, so as to deliver the material on the surface of the liquid in the center of the tank. 8 is a pipe, preferably stationary, through which air or other gas may be delivered to the submerged hood, and having a 45 regulating valve 10. The pipe 8 enters the mouth of the hood, and preferably delivers the gas at a point above the highest perforation, so as to prevent the liquid from entering the pipe, although if the liquid did enter the pipe no particular harm would be 50 done, as it would again be expelled by the air or gas. 11 is an opening in the bottom of the tank through which the treated material may be removed by passing it through the pipe 12 and regulating valve 13. If de-

sired, the material may be returned to the tank for re-treatment through the pipes 14 and 15, or passed on to another similar apparatus, in series, for further treatment, 60 through the pipe 16. Air or other gas is introduced into the pipe 14 through the pipe 17, thus making an air-lift of the pipe 14. Clogging, in the opening 11, in the bottom of the tank 1, is removed or prevented by an 65 air or water jet introduced through the pipe 18. 19 is a launder, through which the liquid in the tank may overflow, or through which the products of the treatment may be removed. 20 is the launder outlet. 70

The operation of the apparatus will now be described when used in the flotation of suitable ores. The tank is filled with water or ore sludge. The hood 2 is rapidly rotated by the pulley 6. The valve 10 is then opened 75 and air or other gas under pressure in the pipe line 9 is forced into the hood, through the pipe 8. The gas, so forced in, will displace a certain amount of liquid in the hood and escape through the perforations 3, but 80 in escaping through the perforations into the liquid of the tank, the gas is atomized in contact with the liquid, due to the rapid rotation of the hood. The speed at which the hood is rotated will vary according to the 85 size of the hood and the material to be treated, but will usually be several hundred revolutions per minute for large hoods and several thousand for the smaller sizes. The idea, in operating the apparatus, is to get the gas 90 in an exceedingly fine state of subdivision, or in other words to atomize it, and atomize it in the liquid. The finer the subdivision, the more effective the application of the gas becomes, but this again may vary according to 95 the material being treated.

The hood may vary in the details of construction, but for the present description the idea is to have the surface of the hood quite smooth, so as not to agitate the liquid any 100 more than is unavoidable, and to use as little power as possible. The hood is not primarily intended as an agitator but as an atomizer. The result will be, that while the liquid circulates quite rapidly with the hood, 105 in its immediate vicinity, the upper part of the liquid in the tank is also circulating, but slowly, and will not be greatly disturbed.

The ore, crushed to a suitable degree of fineness, usually from 60 to 80 mesh, and 110 treated with suitable ingredients to facilitate flotation, such as oil and possibly acid,

- is then introduced into the apparatus through the hopper 7. As already stated, the lower opening of this hopper may be submerged in the liquid, or suspended over the top. In 5 any case the ore passes through the hopper and enters the liquid in the vicinity of the shaft, and as it descends, passes the respective perforations in the hood, and comes in intimate contact with the atomized air or 10 gas. The mineral that will float rises to the surface and appears as a scum 21. The residue, which will not float, passes downwardly between the hood and the tank and enters the outlet 11, where it may be withdrawn 15 through the pipe 12 and valve 13, or elevated through the pipe 14, for re-treatment in the same apparatus, or for further treatment in a similar apparatus in series with it. The scum of mineral matter on the surface of 20 the liquid in the tank, due to the centrifugal motion of the surface of the liquid, is continuously worked toward the launder 19 into which it overflows, and is removed from the launder through the outlet 20.
- 25 If the apparatus is to be used to precipitate metals out of solution, say, to precipitate copper out of its chlorid or sulfate solution with hydrogen sulfid, the hydrogen sulfid is forced into the hood through the 30 pipes 8 and 9, and its flow is regulated by the valve 10. The hydrogen sulfid, escaping through the holes 3, in the rapidly rotating hood, is atomized in contact with the solution, and is effectively applied in such a 35 way that all the hydrogen sulfid will be consumed. The copper solution is introduced into the hopper 7, and as it passes through the tank, comes in contact with the atomized hydrogen sulfid, so that the copper is precipitated as the sulfid while an equivalent 40 of acid is regenerated. The solution, with the precipitate, passes into the bottom of the tank and out through the opening 11; from there it can be conducted to a settling 45 tank through the pipe 12 and the valve 13, or it may be returned to the tank for further treatment if the values are not all precipitated, through the pipes 14 and 15, or it may be passed to another apparatus, in 50 series, for further treatment, through the pipe 16.
- The amount of liquid displaced in the 55 hood by the air or gas is easily regulated by the number and size of the openings or perforations in the hood, and the amount of air or gas introduced. It is desirable to have the perforations near the top of the hood smaller and fewer in number than those nearer the bottom.
- 60 It will be observed from the drawing that there is no mechanical connection between the rotating hood and the pipe 8 through which the gas is introduced into the hood. This is the preferred arrangement, for with 65 a high rotary speed moving connections,

such for example as when the gas is introduced through a hollow shaft, are exceedingly troublesome.

The gas, introduced through the mouth of the hood offers no mechanical trouble of any kind, no matter what the speed of rotation may be. It is desirable, though not necessary, to deliver the gas above the highest perforation in the hood to act as an air seal, or cushion, when the gas in the hood gets low. This can easily be effected by the arrangement shown in the drawing, by having a long collar on the hood and the shaft only part way inserted in this collar.

If the liquid at the top circulates too rapidly or is agitated too violently comparative quiescence may be obtained by the baffles 23. The position of these baffles may be varied, but they are preferably submerged so as to leave the top of the liquid quite clear of obstructions.

Manifestly, the liquid level in the hood will be determined by the pressure of the air or gas introduced into the hood. If the pressure is excessive, the air will bubble out at the sides: This, of course, is to be avoided. If only a small amount of gas is introduced into the hood, say not enough to fill the gas passages, then some liquid will, of course, be ejected with the gas through the gas passages, and at times it may be desirable to operate the apparatus in this way.

It is evident that by regulating the inflow of gas through the pipes 8 and 9, by the valve 10, a very wide variation of operating conditions may be obtained. It would be an easy matter to eject only gas through the gas passages, or, by shutting off the gas entirely to eject only liquid, or, by varying the inflow of gas to eject any desired mixture of gas and liquid, or, by varying the size and position of the passages to eject gas and liquid separately. Ordinarily, however, a mixture of gas and liquid will inevitably be ejected through the passages of the atomizer in the normal operation of the apparatus, and this will usually be the best way to operate it, for, better results are obtainable by ejecting a mixture of the gas and liquid, than by ejecting either, or both, separately.

The apparatus is convenient if a gas other than air is to be used either as applied to precipitation, impregnation of a liquid, or as applied to flotation, for, if such gases are introduced through a hollow shaft, the mechanical connection between the stationary supply pipe and the hollow shaft, at a high rotary speed, is something of a problem. By means of this apparatus the entire difficulty is easily overcome and perfect regulation is obtainable.

With some of the passages in the atomizer, as shown in the drawing, extending

from the central portion of the atomizer toward its periphery, the gas, or gas and liquid, is ejected with considerable violence through the gas passages into the liquid in 5 the tank, and a high degree of atomization is obtainable. If the gas supply is small there will be considerable suction in the passages to draw the liquid in through the lower extremity of the atomizer and forcibly 10 ejecting it toward the periphery and into the liquid in the tank.

I claim:—

1. In apparatus for treating liquids with 15 gases, a tank adapted to contain a liquid, a rotary member, having gas passages arranged with outlets at variable distances from the center and extending from its central portion toward its periphery, suspended within the tank and submerged in the liquid, 20 and means arranged for introducing a gas into the central portion of the rotary member whereby liquid is displaced from the rotary member and gas is forced through the said passages.

2. In apparatus for treating liquids with 25 gases; a tank adapted to contain a liquid; an atomizer having gas passages extending from its central portion toward its periphery and having a continuity of exterior surface 30 between the gas passages, suspended within the tank and submerged in the liquid, means for rotating the atomizer with sufficient speed to finely subdivide the gas in the liquid, means for causing a flow of gas 35 through the gas passages from the central portion toward the periphery.

3. In apparatus for treating liquids with 40 gases, a tank adapted to contain a liquid; an atomizer having a circular periphery and arranged with gas passages extending from its central portion toward its periphery and having continuity of external surface between the gas passages, suspended within the tank and submerged in the liquid; means 45 for causing a flow of gas through the gas passages from the central portion of the atomizer toward its periphery; and means for rotating the atomizer about its axis with the center of the circular periphery as the 50 center of rotation.

4. In apparatus for treating liquids with 55 gases, a tank adapted to contain a liquid; an atomizer having a circular periphery and continuity of external surface and arranged with gas passages extending from its central portion toward its periphery, suspended within the tank and submerged in the liquid; means for causing a flow of gas 60 through the gas passages from the central portion of the atomizer toward its periphery; and means for rotating the atomizer about its vertical axis with the center of the circular periphery as the center of rotation, and with sufficient speed to finely subdivide 65 the gas in the liquid.

5. In apparatus for treating liquids with 70 gases, a tank adapted to contain a liquid; an atomizer having a circular periphery and continuity of external surface concentric with the periphery and arranged with gas 75 passages extending from its central portion toward its periphery, suspended within the tank and submerged in the liquid; means for causing a flow of gas through the gas passages from the central portion of the 80 atomizer toward its periphery; and means for rotating the atomizer about its vertical axis with the center of the periphery as the center of rotation.

6. In apparatus for treating liquids with 85 gases, a tank adapted to contain a liquid, a gas atomizer suspended within the tank and submerged in the liquid, means for introducing a gas in the lower portion of the tank to be atomized by the atomizer in its 90 ascent through the liquid, and an air trap arranged to prevent the liquid from flowing into the gas inlet in the lower portion of the tank.

7. In apparatus for separating minerals 95 from their gangue by flotation, a tank adapted to contain a liquid and the material to be treated, a rotary gas impregnator having a circular periphery and a porous top and arranged with an annular space between it and the sides of the tank, suspended within the tank and submerged in the liquid, means for introducing a gas into the tank thereby displacing liquid in the impregnator and forcing the gas through the porous 100 top of the impregnator, means for rotating the impregnator, and means for feeding the material to be treated near the center of rotation and passing it across the path of the ascending atomized gas in the liquid. 105

8. In apparatus for separating minerals from their gangue by flotation, a tank adapted to contain a liquid and the material to be treated, a rotary gas impregnator having a circular periphery and a porous top 110 and arranged with an annular space between it and the sides of the tank, suspended within the tank and submerged in the liquid, means arranged for passing a gas through the submerged porous top of the 115 impregnator into the liquid above it, means for rotating the impregnator, and means for feeding the material to be treated near the center of rotation and passing it across the path of the ascending atomized gas in the 120 liquid and downwardly through the annular space between the impregnator and sides of the tank.

9. In apparatus for separating minerals 125 from their gangue by flotation, a tank adapted to contain a liquid and the material to be treated, a rotary gas impregnator having a circular periphery and gas passages extending from its interior toward its exterior and arranged with a space between it 130

- and the sides of the tank, suspended within the tank and submerged in the liquid, means arranged for passing a gas through the gas passages of the impregnator from the interior toward the exterior and into the liquid above it, means for rotating the impregnator about its vertical axis, and means arranged for feeding the material to be treated near the center of rotation and passing it across the path of the ascending atomized gas in the liquid and downwardly through the space between the rotary impregnator and the sides of the tank.
10. In apparatus for treating liquids with gases, a tank adapted to contain the liquid, a rotary atomizer comprising a hollow body open at its lower end and having attenuated discharge passages through its wall, said hollow body being journaled in the tank and submerged in the liquid, and means for admitting a regulable quantity of gas under pressure to the hollow body.
11. In apparatus for treating liquids with gases, a tank adapted to contain the liquid, an atomizer comprising a hollow circular body submerged in the liquid and having attenuated discharge passages through the wall thereof, said hollow body having the lower portion of its interior in communication with the tank, and means for introducing gas into the upper portion of the interior of said hollow body.
12. In apparatus for treating liquids with gases, a tank adapted to contain the liquid, a hollow circular rotary body journaled on a substantially vertical axis within the tank and submerged in the liquid, said rotary body having discharge passages through its upper wall portion within the area of its circular periphery, a liquid inlet arranged below said discharge passages, and means for supplying gas to the interior of said hollow member.
13. In apparatus for treating liquids with gases, a tank for containing liquid, a hollow rotary body journaled therein on a substantially vertical axis and having discharge passages arranged at different elevations, said body having its lower part adapted to receive liquid from the tank, and means for supplying gas under pressure to the upper portion of said hollow body.
14. In apparatus for treating liquids with gases, a tank adapted to contain the liquid, a hollow rotary body journaled on a substantially vertical axis within the tank and submerged in the liquid, said rotary body having radial discharge passages arranged at different elevations, and having its lower portion in communication with the tank, and means for supplying gas to the interior of said hollow body.
15. In apparatus for treating liquids with gases, a tank adapted to contain the liquid, a rotary hollow member submerged in the

liquid and having an opening in its lower portion in communication with the tank, said rotary hollow member having discharge passages through its wall arranged at different elevations, whereby gas and liquid will be discharged through said passages according to the liquid level within said hollow member, and means for introducing a regulable quantity of gas into the upper portion of the interior of said hollow member to displace a portion of the liquid therein.

16. In apparatus for treating liquids with gases, a tank adapted to contain a liquid, a permeable surface having a circular periphery and continuity of surface concentric with the periphery and having a multiplicity of gas passages arranged at various distances from a vertical axis suspended within the tank and submerged in the liquid, means for forcing a gas through the gas passages of the permeable surface into the liquid, and means arranged for rotating the permeable surface concentrically about an axis having the central line of the permeable surface as the center of rotation.

17. In apparatus for separating minerals from their gangue by flotation, a permeable surface having a circular periphery suspended within the tank and submerged in the liquid, means for passing a gas through the permeable surface, and means for feeding the material to be treated near the center of rotation to pass over the permeable surface toward the periphery.

18. In flotation apparatus, a tank adapted to contain a liquid, a rotatably mounted permeable surface having a circular periphery and continuity of surface concentric with the periphery and having a multiplicity of gas passages arranged at various distances from the center of rotation suspended within the tank and submerged in the liquid, means arranged for passing a gas through the gas passages in the permeable surface into the liquid above it, means for rotating the permeable surface about its vertical axis, and means arranged for passing the material to be treated across the path of the ascending atomized gas.

19. In apparatus for treating liquids with gases, a tank adapted to contain a liquid, a rotary atomizer suspended within the tank and submerged in the liquid, said atomizer having a circular periphery and having gas passages extending from its interior central portion toward its periphery and arranged with outlets at various distances from the center of rotation, means for causing a flow of gas to the interior of the atomizer, and means arranged for ejecting the gas from the interior of the atomizer through the passages and into the liquid in the tank.

20. In apparatus for treating liquids with gases, a tank adapted to contain a liquid, a rotary member having a circular periphery

and having gas passages with outlets arranged at various distances from the center of rotation suspended within the tank and submerged in the liquid, means for introducing compressed gas into the tank and by the buoyancy of the gas passing it through the gas passages in the rotary member, means for rotating the rotary member about its vertical axis, and a liquid outlet arranged so as to cause a flow of liquid toward the outlet in a direction opposite to that of the ascending atomized gas in the liquid.
